A. SHAEFFER

VIOLIN FINGER BOARD

Filed May 25, 1921

Inventor:
Arling Shaeffer
By Jno. L. Elliott his Atty.

UNITED STATES PATENT OFFICE.

ARLING SHAEFFER, OF CHICAGO, ILLINOIS.

VIOLIN FINGER BOARD.

Application filed May 25, 1921. Serial No. 472,516.

To all whom it may concern:

Be it known that I, ARLING SHAEFFER, a citizen of the United States, and a resident of the city of Chicago, in the county of Cook and State of Illinois, have invented certain new and useful Improvements in Violin Finger Boards, of which the following is a specification.

This invention relates to improvements in the finger boards of stringed instruments played with a bow, such, for example, as the violin, the violoncello and bass-viol, the finger-boards of which are commonly smooth, substantially flat and without any visual indication of the location of any of its frets, with the result that both talented and untalented pupils have heretofore been compelled to devote many years of constant, tiring practice before acquiring the necessary skill while playing the instrument for unhesitatingly locating the pressure of the fingers directly upon the contact place on the finger-board, giving the perfect interval of tone, and as must be done before anyone can successfully play such an instrument.

The object of my invention is to provide the finger-board of every stringed instrument played with a bow, and particularly the violin, with a simple means, visually indicating the location of all of its intervals of tone, and which will enable every pupil, while playing the instrument, to successfully acquire the ability to master the fingering of such an instrument, including double stops and wavering tones, in materially and substantially less time, with less practice, effort and instruction than has heretofore been possible or practicable.

A further object of my invention is to provide for visibly locating the perfect intervals on the finger-board of a violin, by means least marring its usual and commonly accepted appearance, the construction of which frets is such that they have no tendency to ravel or wear and thereby destroy the texture of the strings sooner than at any other given point, nor change the intonations of the instrument.

With these ends in view my invention finds embodiment in certain features of novelty in the construction, combination and arrangement of parts by which the said objects are attained, all as hereinafter fully described with reference to the accompanying drawings and more particularly pointed out in the claims.

In said drawings,—

Fig. 1 illustrates a top plan view of the finger-board of a violin in which my invention finds its embodiment.

Fig. 2 is a side elevation thereof partly in section and

Fig. 3 is a similar view, showing the crest between the grooves somewhat blunter or more flatly rounded than in Fig. 2.

For carrying out my invention, the finger-board 3 is provided transversely with a series of transverse grooves 4, the adjacent sides of which meet and visibly locate the intervals of the scale 5 of the finger-board, which grooves in practice are curved transversely, the width of which grooves therefore successively increase one-eighteenth of an inch from the groove next the keys of the instrument toward the bridge thereof.

The grooves 4 are formed transversely on the arc of a circle; are quite shallow and may be more or less flat at their bottom in order that the pressure of the finger upon any string for depressing it to operative engagement with the contact of the string next forward of the finger need not be greater than is necessary for maintaining the string in its operative position on the predetermined fret, and this at whatever point between the two frets the pressure of the finger may be directed.

The use of grooves, curved more or less, and particularly near their meeting edges, is an important feature of my invention, providing, as they do, a surface conforming to that of the ends of the human finger, for the exertion of minimum finger force for deflecting the strings to operative contact with the visible frets and for the natural movement of the finger between two frets for producing wavering tones and for imparting range to the latter, not possible with the use of frets angular in cross-section, as the latter would mar the instrument to an objectionable extent, which the shallow curved grooves do not.

The finger-board of my invention can be adjusted to any violin having a smooth finger-board, by simply removing the latter and replacing it with the finger-board of my invention, as will be readily understood by bearing in mind that the length of finger-boards varies only with the differing sizes of violins.

It has been found in practice by a number of teachers that they are saved much time and

effort in teaching the fingering of stringed instruments played with a bow, and particularly of the violin, when the violins of the students are provided with my invention, and this whether singly or in classes.

In other words, students of the violin, on finding that, with the use of my invention on their violins, they can pleasingly play their lessons and pieces in a very few weeks, 10 or months, at most, without having to exactly locate any of the intervals with the tips of their fingers, instead of being compelled to constantly practice for years, as others have had to do, quickly have improved 15 to them so much confidence in their ability to play the instrument as to result in an enthusiasm carrying them forward in the well-founded belief of very soon acquiring intuitively the exact location of the intervals of the strings and thereby becoming 20 successful players of the instrument.

Following the use of my invention, numbers of students have not hesitated to assure their teachers that within about a year or 25 less, they experience no difficulty when playing a violin, the frets for which are invisible, to unerringly locate such intervals with their fingers, and seemingly by intuition.

In conclusion, it is to be observed that the 30 grooves, the meeting side edges of which visibly indicate the intervals, are contiguous

ously formed from the material of which the finger board is made, and that the use of metal frets for musical instruments of the character described herein has a constant tendency to wear through and ravel the strings and to produce intonations unnatural and entirely foreign to such instruments, and, furthermore, that metal frets when so used, are an obstruction to quick 40 and changing fingering and are liable to be more or less objectionable to the average player.

Having described my invention, what I claim and desire to secure by Letters Patent is:

1. A finger-board for stringed musical instruments played with a bow, provided with unobstructed concave grooves immediately adjacent each other, the meeting portions of which grooves are blunted and visibly indicate and constitute the several frets for the strings.

2. In a stringed musical instrument played with a bow, a finger-board provided with transverse grooves the edges of which merge one into the other and visibly form and locate the tone intervals on the scale of the finger-board.

In witness whereof, I have hereunto set my hand this 21st day of May, 1921.

ARLING SHAEFFER.
